CLAIM

The ornamental design for an inhaler, as shown and described.

DESCRIPTION

FIG. 1 is a perspective view of the inhaler in a closed position in accordance with our new design;

FIG. 2 is a left side view thereof, the right side view being identical thereto;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of the inhaler with the cover in the opened position;

FIG. 8 is a top plan view with the cover in the opened position;

FIG. 9 is a left side view of FIG. 8, the right side view being identical thereto; and,

FIG. 10 is a perspective view of the inhaler with the cover and cap in the opened position.

FIG. 1

FIG. 3

FIG. 2
